STORE FRONT BAR CONSTRUCTION

Morris Ketchum, Jr., New York, N. Y., assignor
to The Kawneer Company, Niles, Mich., a cor-
poration of Michigan

Application December 14, 1946, Serial No. 716,265

13 Claims. (Cl. 20—56.3)

1

The present invention relates to improvements in metal store fronts and particularly to bars for mounting plate glass windows. The contours or shapes of plate glass store fronts vary considerably, depending on the architectural themes and on the space available at different stores and locations. In such store fronts there is provided a plate glass setting, arranged horizontally for supporting the plate glass from the bottom and for securing it in place at the top. Such fronts also generally include vertically-arranged metal bars for positioning contiguous vertical edges of the plate glass windows. These are known as division, corner and reverse bars and my invention specifically relates to improvements in division, corner and reverse bars.

Bars heretofore manufactured are suitable only for mounting plate glass windows at one predetermined angle and were not adapted to perform the function of resiliently but firmly securing the glass plates at different angles in conformity to various store front designs. For example, division bars are conventionally designed to hold the plates at one hundred and eighty degrees, corner bars at ninety degrees (interior angle) and reverse bars at ninety degrees (exterior angle). But the front lines of various store fronts are not always premised on these three angles. The store fronts vary greatly as to the desired angular relationship between adjoining plates, depending on available space, the architecture of the building, and many other factors. In order to make any real approach to meeting these various requirements of angularity, the manufacturer has heretofore been compelled to produce and carry in stock a large selection of corner bars, a large selection of reverse bars and a large selection of division bars, each designed to secure window plates at only one fixed angle. Alternatively, special bars must be designed and made for specific store fronts.

It is an object of my invention to provide improvements in division bars, corner bars and reverse bars for plate glass store fronts which permit the plate glass windows to be positioned with a wide range of angular relationship and at the same time are adapted firmly but resiliently to support and grip the vertical margins of plate glass store front windows near their contiguous vertical edges in any position desired throughout this range to fit the front lines of the particular store. The accomplishment of this object permits the bar requirements of all types of store fronts to be met with but three standard manufactured lines, with great result-

2

ant savings in engineering and production costs, production costs and inventory costs, and great resultant economies to the user.

It is an object of the invention to provide improved corner bar, division bar and reverse bar constructions which are suitable to the individual needs of every store front, that is, bars which not only permit the securing of plates at the conventional ninety and one hundred and eighty degree angles, but which have sufficient flexibility to hold the plates at other angles within a wide range. In the illustrative embodiments herein shown, the division bar construction secures glass plates at angles of incidence ranging from one hundred and eighty to one hundred sixty-five degrees, and the corner bar and reverse bar constructions herein shown secure plates at angles ranging from ninety degrees to one hundred and sixty-five degrees.

As indicated, it is an essential requirement of bar constructions that they yieldably but firmly grasp the window plates in a weather-tight fashion. This essential requirement conflicts with the desired characteristic of angular flexibility to which this invention is directed. The present invention reconciles these conflicting requirements. The window plates are secured, in accordance with the invention, in any desired angular relationship within a wide range and in a weather-tight, firm but elastic manner.

Another object of the invention is to provide improved bar constructions by which the window plates are yieldably and resiliently, yet firmly so secured that the plates may expand and contract with temperature changes and withstand the strong forces of high-velocity winds and vibratory influences.

It is also an object of the invention to provide a bar construction whereby the window plates may rapidly be secured in or removed from position, a construction which at once is simple, strong, and attractive in appearance.

A further object of the invention is to provide a bar construction in which the face lugs are slidably and adjustably but firmly secured in position relative to the face piece during store front assembly, so that the face lugs need not be manually held while the interior members and exterior members are fastened together.

An object of the present invention is to provide an adjustable face lug which automatically remains in any desired longitudinal position with respect to the face piece.

A further object of the invention is to provide a bar construction satisfying all of the require-

ments of elasticity, strength, flexibility and economy, while at the same time concealing the fastening members from the public.

Other objects and capabilities of the invention will become apparent from the following description of the accompanying drawings in which there is shown an illustrative embodiment of the invention.

In the drawings:

Fig. 1 is a perspective view, partly in section, with the window plates broken away, showing the general arrangement of a typical store front including division, corner and reverse bars in accordance with the invention;

Fig. 2 is a sectional view taken on line 2—2 of Fig. 1, looking in the direction of the arrows;

Figs. 3, 4, 5, 6 and 8 are sectional views of the corner bar shown in Fig. 1 taken, respectively, on line 3—3 of Fig. 2, line 4—4 of Fig. 3 and line 5—5 of Fig. 2, line 6—6 of Fig. 3 and line 8—8 of Fig. 4, looking in the directions of the arrows;

Fig. 7 is a front view of parts of the Fig. 1 corner bar, showing the face lug in position to be pushed downwardly and adjustably secured to the face piece; and

Fig. 9 is a perspective view showing how the corner bar is secured to its bracket.

Referring now specifically to Fig. 1, there is shown a store front construction comprising a suitable glass-setting device 11, glass plate windows 12, 13, 14 and 15, a division bar 16, a corner bar 17 and a reverse bar 18. The window plates are fragmentarily shown. The glass-setting device 11 is conventional and preferably includes a face-molding 19, a suitable glass-supporting block 20 and an interior gutter member 21. The invention with which this application is concerned relates and is shown in the division bar 16, the corner bar 17 and the reverse bar 18.

Each of the bars comprises an individual face piece 23, 24 or 25, a pair of face lugs 26—27, 28—29, and 30—31 (29 being shown in Fig. 3—21, 31 being not shown but identical to 28, 30, respectively), an individual back spring member 32, 33 or 34 and an individual reinforcement or stiffener member 35, 36 or 37. The numerals 23, 26, 32, 35 pertain to division bar 16; the numerals 24, 28, 33, 36 relate to corner bar 17 and the numerals 25, 30, 34, 37 apply to parts of the reverse bar 18. Lugs 27 and 31 are not specifically shown but they are identical to lugs 26 and 30, respectively, and bear the same positional relationship to lugs 26 and 30 as does lug 29 to lug 28 (Fig. 3).

Face piece 23 is formed of sheet metal, preferably aluminum, and has a generally straight cross-section. The sides of the face piece are reversibly bent and terminate in flanges defining channels 39, 40 for the interlocking engagement of face lug 26 with the face piece. The flanges exteriorly provide curved lips 41, 42 against which the plates 12, 13 abut. Face piece 24 is generally curvilinear in cross-section, the center of curvature being in the interior of the store front. It is likewise formed with flanges defining curved glass-abutting lips 43, 44 and channels 45, 46 for interlocking engagement with face lug 28. Face piece 25 is generally curvilinear in cross-section, the center of curvature, however, being on the exterior of the store front. It also has side flanges defining curved glass-abutting lips 47, 48 and channels 49, 50 for interlocking engagement with face lug 32. Face pieces 24 and 25 are also preferably made of sheet aluminum.

The legs of reinforcement members 35, 36 and 37, respectively, are seated adjacent to shoulders 51—52, 53—54 and 55—56 of spring members 32, 33 and 34, respectively, and abut the ledge portions of the back springs, firmly clamping the spring members in position. The face pieces 23, 24 and 25 are drawn inwardly by face lugs 28—27, 28—29 and 30—31, respectively. The reinforcement members, face pieces and back spring members are of preferably the same length. The reinforcement members, back spring members and face lugs are preferably made of steel, sheet aluminum and sheet stainless steel, respectively.

Each of the bars 16, 17 and 18 is secured to the upstanding portion of its individual generally L-shaped mounting bracket 58, 59 or 60, respectively, by a screw 61, 62 or 63, respectively (Fig. 2), and the mounting bracket base portions are secured to the jamb 64 by screws 65—66, 67—68, 69—70, respectively. Fig. 9 shows the detailed assembly of bar 17 and bracket 59, for example. The other bars and brackets are similarly arranged.

It will be understood that bars 16, 17 and 18 are generally similar, the differences between them being attributable to the different ranges of angular relationships at which the various plates are arranged. The bars have generic features which are specifically described in the following detailed description of the corner bar 17.

Referring now specifically to Fig. 5, it will be noted that lips 43 and 44 have curved surfaces in abutment with plates 13 and 14, respectively. Back-spring member 33 is formed with a central longitudinal rectangular U-shaped channel 71 for slidably receiving the complementary rearwardly extending drawing portion 72 of face lug 28. The back spring is formed also with two integral ledges or abutment portions 73 and 74 against which the sides of generally U-shaped reinforcement member 36 abut as member 36 straddles channel portion 71. The margins of spring member 33 are bent rearwardly through ninety degrees to form shoulders 53 and 54 and then bent forwardly and through a curve on the order of two hundred and forty degrees to define resilient rolled spring portions 75 and 76.

Spring portions 75 and 76 yieldably, elastically and resiliently, yet firmly, abut plates 13 and 14, respectively, their exterior curved surfaces contacting the plates. Curved lips 43 and 44 of face piece 24 also abut plates 13 and 14. Plate 13 is elastically yet firmly gripped between lip 43 and spring roll 75. Plate 14 is elastically yet firmly gripped between lip 44 and spring roll 76. These conditions prevail, whether the plates 13 and 14 are at ninety degrees to each other, or some other interior angle between ninety and one hundred and sixty-five degrees, due to the backspring rolls and the curved face-piece lips and the balance of forces. Fig. 2 shows in dashed outlines the conditions which exist when the planes of the plates are at one hundred and sixty-five degrees to each other. This corner bar construction is perfectly balanced so that the compressive stresses between elements 44, 76, and 43, 75 are equalized, whether the angle between the plates is ninety degrees or of greater value. Regardless of their angular relationship the plates are weather-tightly held, within limits of this order, in a manner which enables them to withstand high winds and vibration strains and by a device having a pleasing exterior appearance, the fastening parts being concealed from outside view.

Resiliency is further introduced at other points between the face lug and the back spring by the elastic wings of the face lugs, for example, wings 78 and 79 of lug 28. These wings, the roll springs 75 and 76 and the lips 43 and 44 cooperate to eliminate glass breakage and other undesired effects of dynamic and static shock.

Reference is now made specifically to Figs. 3, 4, 7 and 8 in describing the construction of lugs 28 and 29, which are substantially identical. Face lug 28 is formed with a central substantially rectangular U-shaped drawing portion 72 and the integral resilient wing portions 78 and 79. The fastening screw 80 is protected by sides 81 and 82 of draw portion 72 and by the integral flaps 83 and 84 of side 81. The outer edges of these flaps abut wall 82 and maintain walls 81 and 82 in spaced relationship. Rear wall 85 of the lug has two integral forwardly extending tongues 86 and 87 having opposed ends adapted to form a threaded opening 88 for receiving the complementary threads cut on the shank of screw 89. Projecting upwardly and outwardly from the face lug and toward the front are integral resilient tangs 89 and 90, which compressively bear against the inner wall of face piece 24 (Fig. 8) to maintain lug 28 in any desired longitudinal position relative to the face piece. This feature has important advantages in that undesired slipping of the lugs during assembly or installation is prevented and in that undesired slipping of the face piece after installation is restrained.

The construction and operation of lug 29 are the same as those of lug 28, except that lug 29 preferably has downwardly extending tangs.

In describing the method of assembly of corner bar 17, it will be assumed that plates 13 and 14, jamb 64, bracket 59, base 28 and setting members 19 and 21 are in place. The wings of lugs 28 and 29 are slipped onto face piece 24 in the manner shown in Fig. 7. Lug 29 is preferably slipped onto the other end of the face piece, since its tangs project downwardly. Lug 28 is so positioned that threaded opening 88 will register with apertures 91 and 92 in the back spring 33 and reinforcement member 36, respectively (Fig. 3). Lug 29 is also properly positioned. Then the subassembly of lugs and face piece is placed in the Fig. 1 position, the resilient tangs of the lugs holding them in position relative to the face piece and minimizing the labor cost of performing this operation. Next, the subassembly of reinforcement member 36, back spring member 33 and screws 80, 93 is placed into the Fig. 1 position. When the screws are turned, the face lugs and face piece are drawn to the rear and the back spring and reinforcement member are pushed to the front by the flanged screw heads. The threads on the shank of screw 80, for example, engage the equivalent nut formed by elements 86, 87, 88 (Fig. 7). The tensile forces are transmitted from the screw shanks to the drawing portions, then out through the resilient wings to the face piece, then through its lips to the front of the plates, whereby the plates are exteriorly pushed inwardly. The compressive forces are transmitted from the screw heads to reinforcement member 36, then through the back spring 33 and its resilient spring rolls 75 and 76 to the rear of the plates, whereby the plates are pushed interiorly outwardly. It should be noted that the reinforcement member 36 exerts balanced forces against the resilient ledge portions 73 and 74 of the back spring 33 whereby balanced clamping forces are exerted against the interior sides of

the plates. Drawing portion 72 is symmetrically arranged with respect to the lips 43, 44, whereby balanced clamping forces are exerted against the exterior sides of the plates. This balance is retained over a wide range of variation of the relative angle of the plates. Drawing portion 72 of the lug 28 is slideable in but embraced by channel 71 and this factor tends to maintain the desired perfect symmetry of forces.

When the corner bar is in place, it is secured to bracket 59 by screw 62. Alternately, of course, the members 59, 62, 36, 33 may be first placed in position, the subassembly of members 24, 28, and 29 then placed in position, and screws 80, 93 then drawn up. Disassembly is equally facile and the tangs yieldably permit withdrawal of the face lugs from the face piece.

The vertical height of each face lug is small with respect to the corresponding dimension of members 36, 33 and 24, yet the compressive forces of lips 43, 44 and spring rolls 75, 76 against the plates are well distributed.

All adjustments of the screws 80 and 93 are performed from the interior, but the face piece substantially conceals the fastening elements from the exterior view.

All of the aforementioned advantages are achieved while face piece 24 affords a pleasing, harmonious and attractive appearance.

As is apparent from an inspection of the drawings, the following generic features of the corner bar construction are incorporated in the division and reverse bars: the curved lips bearing on the outside of the plates, the face lugs adjustably slideable in the face pieces, the full protection of the screws by the sides of the face lug drawing portions and integral flaps, the tangs for securely but adjustably positioning the face lugs, the resilient curved spring rolls of the back spring bearing on the inside of the plates, the resilient wings of the face lugs, the balanced bearing of the reinforcement members on the resilient rear ledges of the back spring, the central channel portion of the back spring embracing the projecting drawing portion of the face lug, the adjustable drawing screws, the rapid and economical method of assembly, the balanced stress of the face lug wings on the face piece lips, and the general conformity of the resilient wing shapes to the architectural form of the face piece. In particular, the face piece of each bar has curved glass-abutting surfaces, and the back-spring of each bar has curved resilient glass-abutting spring rolls.

A metallic cylinder 95 acts as a guide for the adjusting screw 80 (Fig. 2), lining up the holes through which the screw passes in members 35 and 32, thus facilitating installation, where desired.

These bar structures are strong and durable and not susceptible to buckling. The reinforcement members 35, 36 and 37 prevent buckling and lend uniform support to the bars, also aiding in effecting a uniform distribution of the gripping forces acting on the glass plate windows.

While there have been shown and described what are at present considered to be the preferred embodiments of the present invention, it will be obvious to those skilled in the art that various modifications and substitutions of equivalents may be made without departing from the teachings of the invention and the proper scope thereof and it is accordingly intended in the appended claims to cover all such changes and

modifications as fall within the true scope of the invention and outside of the scope of the prior art.

Having thus described my invention, I claim:

1. A store front bar for resiliently yet firmly clamping and holding a pair of contiguous window plates throughout a wide range of angular positions, comprising in combination, an exterior face piece member formed with doubled-back side edges defining channels and curved glass-clamping surfaces, one of said surfaces abutting the exterior of one of said plates and the other of said surfaces abutting the exterior of the other of said plates, an interior back-spring member formed with a central rectangular longitudinal channel and ledge portions on each side of said channel and rolled margins defining curved resilient glass-clamping surfaces, one of said surfaces abutting the interior of one of said plates and the other of said surfaces abutting the interior of the other of said plates, an interior rigid reinforcement member disposed behind said back-spring member and formed with a central portion and integral legs abutting said ledge portions, a bifurcated face lug formed with a central drawing portion slidable in but embraced by the walls of said longitudinal channel of said back-spring member and symmetrically arranged resilient wings individually slidably secured in said face-piece channels, and means adjustably connecting said face lug and said reinforcement member for drawing together said face piece and said back spring member, which thereupon resiliently but firmly hold said window plates between said clamping surfaces.

2. A store front bar for clamping and holding a pair of window plates in angular relationship comprising an exterior face member, an interior back spring member formed with a central longitudinal channel and spring rolls on each side of said channel, one of said rolls being adapted to spring grip the interior of one of said plates automatically throughout a wide range of varying angular positions, and the other of said rolls being adapted resiliently to spring grip the interior of the other of said plates automatically throughout a wide range of varying angular positions, an interior rigid reinforcement member disposed adjacent to said back-spring member, a face lug formed with a central drawing portion slidable in but embraced by the walls of said longitudinal channel of said back spring member and with symmetrically arranged wings interlocked with said face-piece, and means adjustably connecting said face lug and said reinforcement member for drawing together said face piece and said back spring member for firmly spring gripping contiguous plates of glass throughout a wide range of varying angular positions of the glass plates.

3. A store front corner bar for resiliently yet firmly clamping and holding a pair of contiguous window plates through a wide range of angular positions between ninety and one hundred and sixty-five degrees comprising a curved exterior face piece member disposed with its convex surface toward the exterior and formed with doubled back side edges defining channels and curved glass-clamping surfaces, one of said surfaces abutting the exterior of one of said plates and the other of said surfaces abutting the exterior of the other of said plates, an interior back-spring member formed with a central rectangular longitudinal channel and ledge portions on each side of said channel and rolled margins defining curved resilient glass-clamping sur-

faces, one of said surfaces abutting the interior of one of said plates and the other of said surfaces abutting the interior of the other of said plates, an interior rigid reinforcement member disposed behind said back-spring member and formed with a central portion and integral legs abutting said ledge portions, a bifurcated face lug formed with a central drawing portion slidable in but embraced by the walls of said longitudinal channel of said back spring member and symmetrically arranged resilient wings individually slidably secured in said face-piece channels, and means adjustably connecting said face lug and said reinforcement member for drawing together said face piece and said back-spring member, which thereupon resiliently but firmly hold said window plates between said clamping surfaces at any angular position within said range.

4. A store front reverse bar for resiliently yet firmly clamping and holding a pair of contiguous window plates throughout a wide range of angular positions between ninety and one hundred and sixty-five degrees comprising a curved exterior face piece member disposed with its concave surface toward the exterior and formed with doubled back side edges defining channels and curved glass-clamping surfaces, one of said surfaces abutting the exterior of one of said plates and the other of said surfaces abutting the exterior of the other of said plates, an interior back-spring member formed with a central rectangular longitudinal channel and ledge portions on each side of said channel and rolled margins defining curved resilient glass-clamping surfaces, one of said surfaces abutting the interior of one of said plates and the other of said surfaces abutting the interior of the other of said plates, an interior rigid reinforcement member disposed behind said back-spring member and formed with a central portion and integral legs abutting said ledge portions, a bifurcated face lug formed with a central drawing portion slidable in but embraced by the walls of said longitudinal channel of said back spring member and symmetrically arranged resilient wings individually slidably secured in said face-piece channels, and means adjustably connecting said face lug and said reinforcement member for drawing together said face piece and said back-spring member, which thereupon resiliently but firmly hold said window plate between said clamping surfaces and in predetermined adjusted angular relation within said range.

5. A store front division bar for resiliently yet firmly clamping and holding a pair of contiguous window plates throughout a wide range of angular position between one hundred and eighty and one hundred and sixty-five degrees comprising a planar exterior face piece member formed with doubled back side edges defining channels and curved glass-clamping surfaces, one of said surfaces abutting the exterior of one of said plates and the other of said surfaces abutting the exterior of the other of said plates, an interior back-spring member formed with a central rectangular longitudinal channel and ledge portions on each side of said channel and rolled margins defining curved resilient glass-clamping surfaces, one of said surfaces abutting the interior of one of said plates and the other of said surfaces abutting the interior of the other of said plates, an interior rigid reinforcement member disposed behind said back-spring member and formed with a central portion and integral legs abutting said ledge portions, a bifurcated face lug formed with

a central drawing portion slidably in but embraced by the walls of said longitudinal channel of said back spring member and symmetrically arranged resilient wings individually slidably secured in said face-piece channels, and screw means adjustably connecting said face lug and said reinforcement member for drawing together said face piece and said back-spring member, which thereupon resiliently but firmly hold said window plates between said clamping surfaces and in predetermined adjusted angular relation within said range.

6. A store front bar construction adapted for holding contiguous edges of large plates of glass throughout a wide range of angular positions comprising, in combination, a rigid interior supporting member consisting of a hollow metal rail having a rear wall portion, a pair of opposite side walls integral therewith and extending forwardly therefrom in spaced relationship with each other and terminating in a front wall comprising a pair of inwardly extending flanges integral with the side walls and lying in a common plane, but spaced apart to form an open central slot of width substantially less than the width of the rail; an inner spring clamping strip disposed along the front wall of the rail with a pair of spaced apart shoulders rearwardly offset exteriorly of the side walls and adjacent thereto, with open cylindrical spring bearing portions extending outwardly from the shoulders and curving inwardly at the marginal edges of said strip to engage the inner surfaces of the glass plates continuously throughout a wide range of varying angular positions of the glass, and a central channel portion of said spring clamping strip extending into the slot in the forward wall of the rail in interlocking relation therewith; an outer clamping strip disposed forwardly of said rail and inner strip and having reverse bends forming internal slide grooves and exterior convexly curved clamping surfaces along its marginal edges, with said convexly curved clamping surfaces being constructed and arranged to engage the exterior surfaces of the glass plates continuously throughout a corresponding range of angular positions; a plurality of spring lugs spaced apart from each other along said outer clamping strip; said lugs each having wing portions slidably engaging the slide grooves of the outer clamping strip and including additional friction means securing the lugs in fixed position thereon; with a narrow central channel portion on each of said spring lugs extending between the contiguous edges of the glass plates and into the channel of the inner clamping strip in interlocking relationship therewith to prevent relative lateral shifting of the inner and outer clamping strip.

7. A store front bar construction adapted for holding contiguous edges of large plates of glass throughout a wide range of angular positions comprising, in combination, a rigid interior supporting member comprising a hollow metal rail having a rear wall portion, a pair of opposite side walls integral therewith and extending forwardly therefrom in spaced relationship with each other and terminating in front surfaces lying in a common plane, but spaced apart to form an open central recess at the front of the rail; an inner spring clamping strip disposed along the front of the rail with open cylindrical spring bearing portions on its marginal edges constructed and arranged to engage the inner surfaces of the glass plates continuously through-

10

out a wide range of varying angular positions of the glass, and a central channel portion of said spring clamping strip centrally positioned with respect to the rail and extending rearwardly into the recess thereof, with the width of the channel in said strip substantially less than the width of the rail; an outer clamping strip disposed forwardly of said rail and inner strip and having reverse bends forming internal slide grooves and exterior convexly curved clamping surfaces along its marginal edges, with said convexly curved clamping surfaces constructed and arranged to engage the exterior surfaces of the glass plates continuously throughout a corresponding range of angular positions, with a plurality of spring lugs spaced apart from each other along said outer clamping strip; said lugs each having wing portions slidably engaging the slide grooves of the outer clamping strip and including additional frictional means securing the lugs in fixed position thereon; with a narrow central channel portion on each of said spring lugs extending between the contiguous edges of the glass plates and into the channel of the inner clamping strip in interlocking relationship therewith to prevent relative lateral shifting of the inner and outer clamping strips.

8. In a store front bar construction adapted for holding contiguous edges of large plates of glass throughout a wide range of angular positions, the subcombination of an interior bar assembly comprising a hollow metal rail having a rear wall portion, a pair of opposite side walls integral therewith and extending forwardly therefrom in spaced relationship with each other and terminating in a front wall comprising a pair of inwardly extending flanges integral with the side walls and lying in a common plane, but spaced apart to form an open central slot of width substantially less than the width of the rail; an inner spring clamping strip disposed along the front wall of the rail with open cylindrical spring bearing portions on its marginal edges constructed and arranged to engage the inner surfaces of the glass automatically throughout a wide range of varying angular positions of the glass, and a central channel portion of said spring clamping strip extending into the slot in the forward wall of the rail in interlocking relation therewith; with perforations spaced at intervals along the rear wall portion of the rail and perforations in the channel portion of the clamping strip in registry therewith, and a tubular guide sleeve extending from each of the perforations in the rail to the corresponding perforation in the channel to facilitate the insertion of fastening screws therethrough.

9. A store front bar for clamping and holding a pair of contiguous window plates throughout a wide range of angular positions comprising an exterior face member, an interior back spring member formed with a central longitudinal channel and ledge portions on each side of said channel and margins shaped to define open cylindrical glass-clamping springs, one of said springs being adapted to abut the interior of one of said plates and the other of said springs being adapted to abut the interior of the other of said plates, an interior rigid reinforcement member of thickness greatly exceeding the thickness of the interior back spring member and disposed adjacent to said back-spring member and formed with a central portion and integral legs abutting said ledge portions, a face lug formed with a central drawing portion slidable

in but embraced by the walls of said longitudinal channel of said back spring member and symmetrically arranged wings interlocked with said face-piece, and means adjustably connecting said face lug and said reinforcement member for drawing together said face piece and said back spring member for the purpose set forth.

10. A device for drawing together the exterior and interior clamping members of a store front bar comprising a single sheet metal face lug formed with a rear wall portion, forwardly extending side wall portions terminating in wings adapted to be interlocked with the exterior clamping member, a screw projecting through said rear wall portion and engaging it to draw said face lug toward the interior clamping member, and integral flaps projecting from one of said side wall portions to the other side wall portion on both sides of said screw, whereby to protect said screw and maintain the rigidity of the side walls.

11. A store front bar construction adapted for holding contiguous edges of large plates of glass throughout a wide range of angular positions, comprising in combination, a rigid supporting member, an inner clamping member having a channel member extending into the rigid support for locking it with the rigid support against horizontal movement and having open cylindrical spring bearing members adapted to engage one surface of contiguous plates of glass and to continuously afford a spring gripping action on the glass throughout a wide range of varying angular positions of the glass, an outer spring clamping member adapted to continuously afford a spring gripping action on the outer surface of the glass plates throughout the corresponding wide range of varying angular positions of the glass in cooperation with the said inner clamping member, a spring connecting member slidably contacting at its ends with said outer clamping member, and provided with an intermediate channel adapted to extend between spaced edges of the contiguous plates of glass and fit into the said first mentioned channel member, and means connecting the rigid support and the said intermediate channel for drawing the connecting member toward the rigid support for tightly spring gripping the glass throughout a wide range of varying angular positions of the glass.

12. A store front bar construction adapted for holding contiguous edges of large plates of glass throughout a wide range of angular positions, comprising in combination, a rigid supporting member, an inner clamping member having means for locking it and the rigid support against relative horizontal movement and hav-

ing open cylindrical spring bearing members adapted to engage one surface of contiguous plates of glass and to continuously afford a spring gripping action on the glass throughout a wide range of varying angular positions of the glass, an outer spring clamping member adapted to continuously afford a spring gripping action on the outer surfaces of the glass plates throughout a corresponding wide range of varying angular positions of the glass in cooperation with the said inner clamping member, a spring connecting member slidably contacting at its ends with the said outer clamping member, and provided with an intermediate channel adapted to extend between spaced edges of the contiguous plates of glass, and means connecting the rigid support and the said intermediate channel for drawing the connecting member toward the rigid support for tightly spring gripping the glass throughout a wide range of varying angular positions of the glass.

13. In a store front bar for clamping and holding a pair of window plates in angular relationship, an interior back-spring member formed with a central longitudinal channel and spring rolls on each side of said channel adapted to spring grip the interior of said plates, an interior rigid reinforcement member of substantially U-shaped cross-section engaging the longitudinal channel of said back-spring member and interlocking with it to prevent relative lateral movement between said back-spring member and said reinforcement member, with a series of perforations spaced apart and in registry with each other in said back-spring member and said reinforcement member, and a plurality of tubes extending between said perforations.
